CLAIM

The ornamental design for a mirrored, slotted phone case, as shown and described.

DESCRIPTION

FIG. 1 is a perspective view of a mirrored, slotted phone case showing the design;

FIG. 2 is a rear view showing the mirror of the phone case of FIG. 1;

FIG. 3 is a top view of the phone case of FIG. 1;

FIG. 4 is a bottom view of the phone case of FIG. 1;

FIG. 5 is a front view of the phone case of FIG. 1;

FIG. 6 is a right side view of the phone case of FIG. 1; and,

FIG. 7 is a left side view of the phone case of FIG. 1.

The broken lines in the figures show unclaimed subject matter only and form no part of the claimed design.
